UNITED STATES PATENT OFFICE.

CHARLES S. SNYDER, OF PHILADELPHIA, PENNSYLVANIA.

HEATER.

Application filed December 13, 1921. Serial No. 522,070.

To all whom it may concern:

Be it known that I, CHARLES S. SNYDER, a citizen of the United States, residing at Philadelphia, in the county of Philadelphia and State of Pennsylvania, have invented certain new and useful Improvements in Heaters, of which the following is a specification.

One object of my invention is to make an improved heater which can be used as a "one-room heater" and as such can be made in a form so as to be readily portable and conveniently connected by a gas hose so as to supply gas to the burner for creating heat.

Another object is to make my improved heater of a simple, durable and neat construction which can be readily manufactured.

These objects, and other advantageous ends which will be described hereinafter, I attain in the following manner, reference being had to the accompanying drawings in which—

Figure 1 is a front elevation of a heater made in accordance with my invention,

Figure 2 is a top plan view of the heater shown in Figure 1,

Figure 3 is an enlarged sectional elevation taken on the line 3—3 of Figure 2,

Figure 4 is a sectional plan view taken on the line 4—4 of Figure 3,

Figure 5 is a fragmentary sectional inverted plan view taken on the line 5—5 of Figure 3,

Figure 6 is an enlarged fragmentary sectional elevation taken on the line 6—6 of Figure 2,

Figure 7 is a fragmentary elevation of a portion of the central drum,

Figure 8 is a top plan view of the pedestal portion of said central drum,

Figure 9 is a fragmentary sectional elevation of the joined parts of the central drum, taken on the line 9—9 of Figure 4, and

Figure 10 is a fragmentary section taken on the line 10—10 of Figure 3.

Referring to the drawings, 12 represents a circular base forming a part of my improved heater; said base including a circular band 13 preferably made of sheet metal having holes 14 extending therethrough above its bottom; said holes being spaced apart and allowing air to enter the space within the base when the base is set upon a floor.

The lower edge of the band is preferably

turned so as to provide a reinforcement and if desired a core wire 15 can be inserted within the turned portion for strengthening purposes. The upper end of the band 13 is bent in embracing position around the outer edge portion of a circular base plate 16; said base plate being preferably made of cast metal and having three upwardly projecting circular ribs 17, 18 and 19; these ribs being made concentric; the rib 17 being innermost and the rib 18 being positioned between the rib 17 and the outer rib 19.

An outer cylindrical shell or jacket 20, which is preferably made of sheet metal, has its lower edge supported on the top of the base plate 16 immediately surrounding the rib 19 so as to snugly fit around said rib 19. An intermediate shell 21, which is made cylindrical and preferably of sheet metal, is positioned within the outer shell 20 and has its lower edge supported on the top of the base plate 16 and snugly surrounds the intermediate rib 18.

An inner cylindrical drum 22 includes a cylindrical section 23 of copper, preferably sheet copper, and this section is positioned directly above a pedestal section 24 of said drum 22. This pedestal section is made in the form of a cylinder with its lower edge supported on the top surface of the base plate 16 so as to snugly surround the innermost rib 17. A burner supporting partition 25 is made in the form of a plate interposed between the bottom of the section 23 and the top of the pedestal section 24. The top edge of the pedestal section 24 has an outwardly turned flange 26 around which the outer edge portion of the burner supporting partition is bent so as to connect the partition 25 to the pedestal section 24. The drum section 23 has tongues 27 in the form of small plates which are attached thereto and the lower ends of these plates are adapted to extend through slots 28 in the partition 25 so as to prevent relative rotation or lateral displacement between the section 23 and the pedestal section 24 of the central drum 22. At the same time it will be noted that the central drum can be readily lifted apart from the pedestal section 24 when it is desired to do so as will be rendered more obvious from the following description.

A perforated top plate 29 has a projecting flange 30 which rests on the upper edge of the jacket 20; the inner perforated body 110

portion 31 of said top plate fitting within the upper portion of said jacket 20 and resting upon the top edges of the intermediate shell 21 and the drum 22. This top plate 5 has circular flanges 32 and 33 which respectively depend within and fit the intermediate shell 21 and drum 22 so that said shells and drums will be kept in proper spaced position at their tops as well as at their bottoms. 10 Tie bolt rods 34 extend through the top plate 29 and base plate 16 and have nuts on their lower ends which engage the lower surface of the base plate within the confines of the base band 13; the upper ends of the tie bolt rods being provided with heads which fit countersunk portions in the top plate 29. The tie bolt rods preferably extend through the space between the outer and intermediate shells and thereby hold the base plate 15 and top plate together and also serve to prevent the jackets and drum from moving vertically.

The perforations in the top plate 29 extend over the spaces between the shells, the 25 drum and the intermediate shell, and the space within the drum 22. The intermediate shell has elongated notches 35 which extend upward and form communication between the lower part of the space 36 between the 30 shells and with the lower part of the space 37 between the intermediate shell and the drum at positions above the base plate 16. The pedestal section 24 of the drum 22 has holes 38 which form communication with the 35 space within the pedestal section and the lower part of the space 37. The partition 25 has holes 39 which form communication with the space within the pedestal section 24 and the space within the section 23.

40 A burner 40 is positioned within the section 23 of the drum 22 and rests on the top of the partition 25; said burner having a bolt 41 which extends through the partition and is secured by a nut 42 within the 45 pedestal section, which engages the under surface of said partition. This burner 40 has a supply tube or stem 43 which projects outward through an upwardly extending notch 44 in the lower end of the section 23 50 of the drum and through holes 45 and 46 in the shells 20 and 21. This tube, at a position outside of the jacket 20, preferably includes an air regulating shutter 46^a and a gas inlet valve 47; said valve having an 55 extension 48 for the connection of a gas supply hose.

The shell 20 has an aperture 49 which serves as a doorway which can be closed by a slidable door 50 movable in guides 51 which 60 are secured to the outer surface of the shell 20, as clearly shown in Figure 1. The intermediate shell 21 has a horizontally elongated slot 52 directly inward from the door aperture 49 and the section 23 of the drum 22 has a smaller hole 53 in central registry

with the slot 52. The arrangement is such that a person holding a lighted match in their hand can insert the hand through the aperture 49; the fingers extending through the slot 52 and the match extending through the hole 53 so that the flame of the match can be held near the burner when it is desired to light the same.

70 The heat deflecting and radiating hood 54, which is preferably made of sheet copper and of conical form with the apex pointing downward, is located within the section 23 of the drum 22 at a position adjacent the top of said drum and spaced below the top plate 29. This hood is supported, at 75 spaced distances apart, by bracket arms 55 which are, in turn, secured to the drum by screw bolts 56. The portion of the hood of largest diameter is of less diameter than the 80 internal diameter of the section 23 of the drum so that there is a space surrounding the peripheral edge 57 of the hood; the hood 85 also preferably being perforated as shown at 58.

A suspension bolt 59 passes centrally 90 through the hood 54 and at its lower end supports a disk 60; said disk being positioned directly above and spaced from the burner 40. The disk 60 has spacing fingers 61 extending radially therefrom, as shown in Figure 5, for engagement with the inner wall of the drum section 23. The suspension bolt 59 projects through an upturned boss 62 and has a nut 63 on its lower end below the disk so as to support the disk in 95 a position below the hood 54. A core of fire brick or other refractory material 64 has a hole through which the suspension bolt 59 passes; said core 64 being positioned 100 above the disk 60 and resting on the boss 105 62. Thus the core 64 is positioned between the disk 60 and the hood 54. As illustrated, I have shown the top of the core or block 64 provided with transversely extending 110 grooves 65 immediately below the hood 54; thus forming an extended radiating surface 115 for heat absorbed from the burner 40. The outer surface of the core 64 preferably tapers downward from a size of greater diameter than the disk so that the heat from 120 the burner will be deflected by the upwardly flaring outer surface of the disk toward the copper drum section 23 and the heat encountered by the lower part of the hood will be partly deflected radially into engagement with the copper section 23 of the 125 drum and thus the drum will become extremely hot during the use of the heater and the heat radiated will pass upwardly through the space 37 between the drum and the shell 21; the space 36 having air therein which is comparatively cool. Thus comparatively cool air will pass downward through the perforated plate 29 into the space 36 and will pass into the space 37.

through the notches 35. This air will absorb the heat radiated from the drum and will pass upward through the space 37 and outward through the perforations in the plate 29 immediately above the space 37.

I also preferably provide holes 66 in the drum section 23 at a level below the edge 57 of the hood 54 so that a portion of the heat will directly pass through the holes 66 into the space 37 and will then pass out through the perforated top plate. Furthermore a great portion of the radiated heat from the top of the hood 54 and a portion of the direct heat through the holes 58 will pass directly from the interior of the drum section 23 out through the perforations in the top plate 29. Also a certain portion of the heat will pass between the edge 57 and the inner wall of the drum section 23 and this heat will also pass directly out through the perforations of the top plate 29. It will be noted that a portion of the air from the bottom part of the spaces 36 and 37 will pass into the pedestal section through the holes 38 and will then pass upward through the holes 39 into the drum section 23 where it will become heated and pass upwardly through the drum section 23.

By making the hole 45 in the lower end of the intermediate shell 21 in the form of a notch of the same general character as one of the notches 35, it is an easy matter to assemble the parts since the pedestal section 24 with the burner thereon can be positioned on the base plate 16, after which the section 23 can be lowered, then the intermediate shell 21 can be lowered into position and finally the outer shell 20 can be positioned so that the extreme outer end of the tube 43 will register with the hole 46 and then the nipple connection for the air adjuster and valve can be applied by screwing the same into the end of the burner tube 43. The several parts can be quickly assembled and in the actual use of the heater I have found that great heat can be secured at a low cast. Furthermore by arranging the base and providing the holes 14, the space below the base plate will be kept comparatively cool so that the heater can be set directly on a floor and the base will be comparatively cool at all times.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

65 1. A heater of the character described in-

cluding an inner drum; a heating agent therein; an outer shell surrounding said drum; an intermediate shell surrounding said drum and being spaced between said drum and the outer shell, said structure providing a passageway between lower portions of the space between the drum and the intermediate shell and between the intermediate shell and the outer shell, and also passages through said drum below said heating agent; and heat-deflecting means positioned above said heating agent within said drum whereby the heat from the agent will be deflected toward the inner wall of said drum; substantially as described.

2. A heater of the character described including an inner drum; a heating agent mounted therein, an outer shell surrounding said drum; an intermediate shell spaced between said drum and the outer shell, there being air passages from the lower part of the outer space to the intermediate space; and heat deflecting means positioned above said heating agent within said drum for deflecting heat from said agent toward the inner wall of said drum, said drum having radial perforations for leading heat from said deflecting means to the space around the drum; substantially as described.

3. A heater of the character described including an inner drum; a heating agent mounted therein; an outer shell surrounding said drum; an intermediate shell spaced between said drum and the outer shell, there being air passages from the lower part of the outer space through the intermediate shell and from the intermediate space through the drum, leading air below the heating agent; and heat deflecting means including a downwardly tapering hood positioned above said heating agent within said drum for deflecting heat upwardly toward the inner wall of said drum, said drum having radial perforations for leading heat from said deflecting means to said space around the drum; substantially as described.

4. A heater of the character described including an inner drum; a heating agent supported on the inside of said drum; an outer shell surrounding said drum; an intermediate shell spaced between said drum and the outer shell, there being air passages from the lower part of the outer space to the intermediate space, and from the intermediate space through the drum to the space below the heating agent; and heat deflecting means mounted above said heating agent on the inner side of said drum whereby the heat from the agent will be deflected toward the inner wall of said drum, said heat deflecting means including a downwardly tapering hood and a core of refractory material supported by said hood; substantially as described.

5. A heater of the character described in-

cluding an inner drum; a heating agent therein; an outer shell surrounding said drum; an intermediate shell surrounding said drum and being spaced between said drum and the outer shell, said structure providing a passageway between lower portions of the space between the drum and the intermediate shell and between the intermediate shell and the outer shell; and heat-deflecting means positioned above said heating agent within said drum whereby the heat from the agent will be deflected toward the inner wall of said drum, said heat-deflecting means including a hood tapering downward and being provided with small heat passages, a suspension bolt depending from said hood, and refractory material supported by said suspension bolt below the hood, said refractory material tapering downward; substantially as described.

6. A heater of the character described including an inner drum; a heating agent therein; an outer shell surrounding said drum; an intermediate shell surrounding said drum and being spaced between said drum and the outer shell, said structure providing a passageway between lower portions of the space between the drum and the intermediate shell and between the intermediate shell and the outer shell; and heat-deflecting means positioned above said heating agent within said drum whereby the heat from the agent will be deflected toward the inner wall of said drum, said heat-deflecting means including a hood tapering downward, a suspension bolt depending from said hood, and refractory material supported by said suspension bolt below the hood, said refractory material having its upper part grooved to increase its radiating surface below said hood; substantially as described.

7. A heater of the character described including an inner drum; a heating agent therein; an outer shell surrounding said drum; an intermediate shell surrounding said drum and being spaced between said drum and the outer shell, said structure providing a passageway between lower portions of the space between the drum and the intermediate shell and between the intermediate shell and the outer shell; and heat-deflecting means positioned above said heating agent within said drum whereby the heat from the agent will be deflected toward the inner wall of said drum, said deflecting means including a hood, said drum having perforations below said hood communicating with the upper part of the space between said drum

and the intermediate shell; substantially as described.

8. A heater of the character described including an inner drum; a heating agent therein; an outer shell surrounding said drum; an intermediate shell spaced between said drum and the outer shell, said structure providing air passages to the outer space and the intermediate space formed by said shells and drum; and heat deflecting means positioned above said heating agent within said drum to deflect heat toward the inner wall of said drum, said deflecting means including a tapering hood and a core of refractory material mounted below the taper of said hood, said drum having radial perforations intermediate said hood and core for leading heat into the space surrounding said drum; substantially as described.

9. A heater of the character described including a drum, said drum having a pedestal section and an upper section, said pedestal section having flanges and a partition plate clamped over said flanges; and a heating agent supported upon said partition, said pedestal having holes therein for the admission of air, said partition having holes forming communication between the interior of the pedestal section and the interior of the upper section of the drum, said partition having slots therein, said upper section of the drum having tongues extending through said slots; substantially as described.

10. A heater of the character described including a drum, said drum having a pedestal section and an upper section, said pedestal section having a partition providing a top; and a burner supported upon said partition, said pedestal having holes therein for the admission of air, said partition having holes forming communication between the interior of the pedestal section and the interior of the upper section of the drum, said upper section of the drum having a notch, said burner having a supply tube extending outward through said notch and tongues on said upper drum section extending through slots provided in said partition to facilitate removing said upper section and said burner, substantially as described.

In testimony whereof I have signed my name to this specification in the presence of two subscribing witnesses.

CHARLES S. SNYDER.
